UNITED STATES PATENT OFFICE.

JEAN BAPTISTE DAUDELIN, OF FALL RIVER, MASSACHUSETTS.

SHUTTLE.

Application filed January 18, 1922. Serial No. 530,190.

To all whom it may concern:

Be it known that I, JEAN BAPTISTE DAUDELIN, a citizen of the United States, residing at Fall River, county of Bristol, Commonwealth of Massachusetts, have invented certain new and useful Improvements in Shuttles, of which the following is a specification.

This invention relates to shuttles, and particularly to an automatically threading shuttle for use in weft replenishing looms, and consists in the novel construction, combination and relation of parts described and illustrated in the accompanying specification and drawings, and particularly pointed out in the appended claims.

More specifically, my present invention relates to the means for guiding the weft from the weft carrier to the eye of the shuttle. According to my invention, I mount in the shuttle throat between the weft carrier and eye a guide in the form of a helix which is preferably wound in a direction opposite to the unspooling action of the weft from the weft carrier so that the rotary motion of the weft as it is drawn from the weft carrier causes the weft to work inwardly towards the center of the helix where it is held against improper escape.

The construction and operation of my invention, together with selected embodiments which well illustrate the principles involved, are described and illustrated in the accompanying specification and drawings, throughout which like reference characters are correspondingly employed, and in the drawings:

Figs. 1 and 2 are plan and side views, respectively, of the threading end of an automatically threading shuttle of standard type equipped in accordance with my invention.

Fig. 3 is a perspective view of the automatic threader removed from the shuttle and particularly showing the weft guide, and

Figs. 4 and 5 are detail views of the eye piece removed from the shuttle.

I have indicated at 1 the threading end of an automatically threading shuttle of standard type, at 2 the shuttle throat, and at 3 a filled weft carrier.

Mounted in spaced holes let through the bottom wall of the shuttle throat in approximately the longitudinal axis thereof, are respectively the depending journals 4 and 5 of an eye piece E and a threader T.

The eye piece may be made of porcelain and is disposed to lie transversely of the shuttle throat with its delivery end disposed substantially flush with the outer face of one of the shuttle walls. Preferably, such eye piece is of one piece construction, and consists of a horizontally disposed body portion 8 from which depends the journal 4. The upper face of the body portion 8 is flattened as indicated at 9, Fig. 4, and beyond the flat the body 8 extends as a vertically disposed snubbing post 10 past which the weft from the bobbin runs into the delivery passage 11 of the eye piece. The passage 11 is formed as a slot cut vertically in the body of the eye piece beyond the post 10, leaving spaced side walls 6^a and 6^b. The wall 6^a of the eye piece farthest removed from the weft carrier, is laterally cleared away adjacent the post 10 to provide a weft inlet through which the weft twisting past said post 10 from the weft carrier enters the slot 11. Said wall 6^a is cut away along its upper edge to lie below the plane of the opposite wall 6^b, as indicated at 13, whereby to insure positive entry of the weft into the passage 11.

The delivery end of the eye itself is undercut as indicated at 14, Fig. 5, leaving overhanging shoulders 15 and 16 effective to prevent escape of the weft from the slot 11 by a direct upward lifting movement.

The threader T is preferably a sheet metal casting comprising vertically disposed inner and outer side walls 17 and 19, respectively, connected at their bottom edges by a horizontal web 18 and at their top edges by a horizontally disposed top wall or cover 28, (Fig. 3). The inner side wall 19 is shorter than the opposite wall 17 providing therewith and with the top wall 28 an open-ended recess 20 within which is mounted a weft guide 21.

In the embodiment shown in Fig. 3, the guide is laid within said recess 20 as a helix consisting of a plurality of helically wound spaced superposed turns. The outer end of the helix is bent substantially vertically downward as indicated at 22 and hooked under or otherwise secured to the wall 19 of the casting. The deflection of the anchoring portion 22 from the body of the guide provides a weft inlet slot 29 through which the weft passing down the rounded face of the outermost turn or convolution of the coil enters the guide.

The helix is preferably wound in a direction opposite to the unspooling action of the weft. As the weft unwinds, it works its way towards the center of the guide where 5 it is held against improper escape.

The cover plate 18 of the casting is preferably extended horizontally, as indicated at 23, to overhang the guide coil 21 and maintain overhead bearing thereupon.

10 Beyond the forward end of the guide 21 the cover plate 18 of the threader is provided with a downwardly extending guide surface 24 which is disposed substantially in line with the outer side wall 17 of the 15 threader and past which the weft twists and is directed into the slot 11 of the eye piece.

When the threader and eye piece are assembled within the shuttle, the guide surface 24 fits over the forward edge of the 20 snubbing post 10 of the eye piece and said post itself is disposed in the space separating said guide surface 24 from the adjacent vertical forward edge of the wall 17 of the threader.

25 Beyond the guide surface 24 the top wall of the threader is turned downwardly as a horn 25 offset relative to said guide surface and between which and the guide surface 24 the weft passes into the eye piece.

30 At the delivery end of the eye piece the cover 18 of the threader is turned down as a tongue 26 which overlies the slot 11 of the eye piece and with the shoulders 15 and 16 thereof prevents upward movement of the 35 weft. The under edge of the tongue 26 is preferably notched centrally as indicated at 27 to overlie the threading passage 11 of the eye piece.

The threader itself is fixed in the shuttle 40 by a screw 30 which passes through the walls 17 and 19.

In threading the shuttle, the weft is drawn along the rounded outer face of the 45 guide 22 between the guide surfaces 24 and 25 of the threader and the post 10 of the eye piece into the passage 11 of the eye piece.

50 As the weft passes into the eye piece, it slides down the outer convolution of the guide 21 and works itself through the passage 29 towards the center of the helix.

55 While I have shown and described my invention in its adaptation to an automatically threading shuttle, it will be understood that the principles involved are applicable to a hand threading shuttle, and that the invention is to be so construed.

Various other modifications in the form and construction of my device may obviously be resorted to without departing from the 60 spirit of my invention if within the limits of the appended claims.

What I therefore claim and desire to secure by Letters Patent is:

65 1. In an automatically threading shuttle having a weft carrier, an eye, and a threader

located between said weft carrier and eye, a guide carried by said threader and consisting of a plurality of spaced helical turns laid in a direction opposite to the unspooling action of the weft whereby the weft will automatically work itself inwardly towards the center of the guide as it runs from the weft carrier. 70

2. In an automatically threaded shuttle having an eye piece, a threader comprising a spaced horizontal top wall, a depending substantially vertical wall and an extension of said vertical wall spaced therefrom and defining therewith and with the top wall a recess, and a guide mounted in said recess and consisting of a plurality of spaced helical turns, the outer turn being extended as an attaching portion engaged with said extension of the vertical wall of the threader. 75 80

3. In an automatically threaded shuttle having an eye piece, a threader comprising a spaced horizontal top wall, a depending substantially vertical wall and an extension of said vertical wall spaced therefrom and defining therewith and with the top wall a recess, and a guide mounted in said recess and consisting of a plurality of spaced turns. 85 90

4. In an automatically threading shuttle having an eye piece, a threader consisting of a substantially horizontal top wall, a depending side wall, a horizontal bottom wall at the lower edge of said side wall and a substantially vertical side wall rising from said bottom wall and defining with said opposite wall and said top and bottom walls an open ended recess, a guide mounted in said recess and consisting of a plurality of spaced turns, the outer turn extending as an attaching portion disposed against said upturned side wall and fastened thereto. 95 100

5. In an automatically threading shuttle having an eye piece, a threader consisting of a substantially horizontal top wall, a depending side wall, a horizontal bottom wall at the lower edge of said side wall and a substantially vertical side wall rising from said bottom wall and defining with said opposite side wall and said top and bottom walls an open ended recess, a guide mounted in said recess and consisting of a plurality of spaced turns; the outer turn extending as an attaching portion disposed against said upturned side wall and fastened thereto, and a pair of spaced thread deflecting surfaces extending from said top wall 11 of the threader beyond said guide for deflecting the weft into said eye. 11

6. In an automatically threading shuttle, an eye piece having a snubbing post and a threading passage beyond said post, a threader consisting of a substantially horizontal top wall, a depending side wall, a horizontal bottom wall at the lower edge of said side wall and a substantially vertical side wall rising from said bottom wall and 11

- defining with said opposite side wall and said top and bottom walls, an open ended recess, a pair of spaced thread deflecting surfaces extending from said top wall of 5 the threader adjacent said snubbing post, and a guide mounted in said recess of the threader in rear of said deflecting surfaces.
7. In an automatically threading shuttle, an eye piece consisting of a member having 10 a substantially flat surface over which the thread runs and having between the ends of said surface a substantially vertical snubbing post, said member beyond said snubbing post having a pair of spaced walls and 15 the space between said walls providing a thread passage.
8. In an automatically threading shuttle,

an eye piece consisting of a member having a substantially flat surface over which the thread runs and having between the ends 20 of said surface a substantially vertical snubbing post, said member beyond said snubbing post having a vertical slot providing a thread passage, and the wall of said slot at the opposite side thereof from the snubbing 25 post being laterally cleared away to provide a thread inlet port opening into said slot.

In testimony whereof I affix my signature in presence of two witnesses.

JEAN BAPTISTE DAUDELIN.
